UNITED STATES PATENT OFFICE.

THOMAS LEAVITT, OF EVERETT, MASSACHUSETTS.

IMPROVEMENT IN PRINTING-PRESSES.

Specification forming part of Letters Patent No. 117,088, dated July 18, 1871.

To all whom it may concern:

Be it known that I, THOMAS LEAVITT, of Everett, in the county of Middlesex and State of Massachusetts, have invented certain Improvements in Printing-Presses, of which the following is a specification:

My invention relates to the hanging of the reciprocating platen, in its contact in backward motion with the projections on the frame, to the arm upon which the platen is hung, and in the manner of adjusting the connecting-rods.

Figure 1 is a side elevation of a machine embracing my invention. Fig. 2 is a transverse section of the same. Fig. 3 is a vertical section of same.

A is the frame; B, the bed; C, the platen; D, connecting-rod; E, projection on the frame; F, an arm; G, a spiral spring; I, a crank-wheel; J', a power-wheel; h, an adjusting-screw; i, spiral spring; H, driving-wheel; I, pinion-wheel; J, cam; K, friction-wheel.

By revolving the power-wheel in either direction the cam J is brought in contact with the friction-wheel K, which forces the bed B toward the platen C. When the bed has acquired a

perpendicular position the form of the cam is such as to rigidly affix it, both while receiving the ink and while receiving the impression. The platen is brought in close connection to the bed by the connecting-rods D and crank-wheels I, while the cam permits the bed to remain stationary. When an impression has been taken the cam liberates the bed, and the spiral spring G causes it to recede from the platen. At the same time the crank-wheels, by means of the connecting-rods, carry the platen from the bed till the projections E on the frame cause it to assume the position shown in Fig. 1. By means of the adjusting-screws h and spiral springs i in the ends of the connecting-rods the platen is brought to an accurate adjustment with the bed.

What I claim as my invention, and desire to secure by Letters Patent, is—

The combination of the cam J with the connecting-rods D, substantially as and for the purpose set forth.

THOMAS LEAVITT.
